To all whom it may concern:

Be it known that I, Herman B. Welch, a citizen of the United States, of West Bend, in the county of Washington and State of Wisconsin, have invented a new, original, and ornamental Design for a Billfold, of which the following is a specification, reference being had to the accompanying drawing, forming part thereof.

In the drawing:

The single figure is an elevation of the front

I claim:

The ornamental design for a billfold, as shown and described.
